A. LE PRINCE.

WALL PAPER.

No. 15,247.

Patented Aug. 12, 1884.

UNITED STATES PATENT OFFICE.

AUGUSTIN LE PRINCE, OF NEW YORK, N. Y.

DESIGN FOR WALL-PAPER.

SPECIFICATION forming part of Design No. 15,247, dated August 12, 1884.

Application filed April 11, 1884. Term of patent 3½ years.

To all whom it may concern:

Be it known that I, AUGUSTIN LE PRINCE, a citizen of the Republic of France, residing in the city of New York, county and State of New York, have invented and produced a new and original Design for Wall or Ceiling Covering, which is especially intended as a frieze.

The drawing represents a front plan view of the design.

10 The design is in the Persian style, having a border in the style of Louis XVI. It consists of scrolls *a*, representing a symmetrical figure, taking the form of two hearts placed horizontally and joined by a diamond-shaped figure at their pointed ends *b*. Entwining the outline are continuous scrolls *c*, in certain places forming volutes, the extension of which laterally form circular and double **E**-like spaces *d* at regular intervals and in symmetrical order.

15 20 The double **E**-shaped spaces *d* are ornamented with tendrils and leaves *e*. The design, as thus far described, is continued or repeated throughout the frieze, being separated at regular intervals by a stellate circular figure hav-

ing its central field occupied by a figure composed of four radiating leaves, *g*, and four club-shaped figures, *h*. Above and below the design are bands of scrolls *i*, with volutes entwined in such a manner as to form circles *k* and ovals *l*, each of which has for a center a rosette or double leaflet, *m*. The interstices of the design are filled in with a groundwork of overlapping scales. The upper and lower borders have a similar design, consisting of a series of rods, *n*, having a ball, *o*, at their junction. These rods are entwined by a double band of ribbon, *p*, which form spaces having for their centers the balls last referred to. The interstices of the design are filled in with a groundwork of fine horizontal lines.

I claim—

The design for a wall or ceiling covering, shown in the print accompanying this description.

AUGUSTIN LE PRINCE.
